PROCESS FOR THE RECOVERY OF
HYDROCARBONSPercival C. Keith, Peapack, N. J., assignor to The
M. W. Kellogg Company, Jersey City, N. J., a
corporation of Delaware

Application October 26, 1940, Serial No. 362,993

4 Claims. (Cl. 62—175.5)

This invention relates to the treatment of hydrocarbon mixtures containing normally liquid hydrocarbons, normally gaseous hydrocarbons of relatively high boiling points and lower boiling normally gaseous hydrocarbons which are relatively difficult to liquefy such as methane and ethane. More particularly, the invention relates to a process wherein a mixture of such hydrocarbons, existing under a relatively high pressure, is expanded to facilitate separation of high-boiling constituents thereof, and residual constituents are recompressed to the original pressure.

An object of the invention is to provide for the recovery of normally liquid hydrocarbons and relatively high boiling normally gaseous hydrocarbons from such mixtures by a process wherein the net energy consumed in the process is at a minimum and is supplied to the process in a simple and economical manner.

While my invention is of general application it is particularly useful in connection with oil field exploitation. When the drilling of a well results in the discovery of a large reservoir of natural gas for which there is no immediate market, legal restrictions may, and principles of conservation do, forbid extraction of the more desirable relatively high boiling constituents from the gas unless the residual portion, ordinarily comprising hydrocarbons having 3 or less carbon atoms per molecule, is returned to an underground reservoir. Frequently reservoirs of natural gas are found under pressures of 2000 pounds to 3000 pounds per square inch or higher. Under these circumstances it is generally preferable to expand the gases to a pressure below 2000 pounds per square inch prior to any separation steps in order to obtain more selective separation of the constituents desired to be recovered. Separation is less selective at relatively high pressures because differences in the vapor liquid equilibrium constants of the hydrocarbons tend to diminish as the critical pressure approaches. However, the advantage of improved selectivity at lower separation pressures is obtained at the expense of recompressing the residual hydrocarbons to be returned to an underground reservoir.

In accordance with my improved process energy derived from the expansion of the original mixture from its relatively high pressure is utilized for recompressing the residual gases, a substantial portion of the energy thus derived from the expansion of the original mixture having been added thereto in the form of heat.

A more detailed explanation of one embodiment of the invention will now be given with particular reference to the treatment of high pressure well gas and apparatus suitable therefor 5 is shown in diagrammatic elevation in the annexed drawing. It is to be understood, however, that this is chosen solely for illustrative purposes, as the invention may take many forms and is not limited to the particular flow arrangement shown.

It is usually not economical to treat well gas containing less than about .2 gallon of butane and heavier hydrocarbons per thousand cubic feet. The richer gases may be accompanied by 15 greater or less amounts of hydrocarbons in the liquid state particularly after an extended pipe line run during cold weather, and it is to be understood that the term "well gas" as used herein may include the total fluid withdrawn from a 20 well, whether or not some condensation has occurred.

Referring now to the drawing, well gas under pressure is passed through line 1 to a heat exchanger 2 wherein it undergoes a preliminary 25 heating step. The gas then passes through line 3 to a heater 4, which may be of any suitable type, such as a coil heated by hot products of combustion, wherein the gas is heated to a temperature in conformity with the requirements of 30 subsequent steps of the process, as will be herein-after explained. The heated gas under pressure is passed to a work engine 5, which may be a reciprocating expander, turbine, or the like, wherein 35 its pressure is reduced and wherein at the same time it is caused to generate mechanical energy. Upon expansion the gas undergoes a lowering in temperature but in most cases will still be capable of helping to heat the incoming well gas, and this is accomplished in the ex-changer 2. The exchanger has an additional advantage in that it assists in cooling the expanded gas to the temperature at which it is desired 40 that the subsequent separating step shall be effected. Continuing through line 1 the partly cooled gas is cooled further if necessary by means of the cooler 8 and thence by line 9 is introduced 45 into a separating drum 10 wherein, in the event that the gas is below its dew point, any accompanying condensate is separated out and withdrawn through line 11.

The cooled gas free of condensate continues 50 through line 12 and into the base of an absorber 13. A suitable absorbent medium, conveniently 55 one derived from the heaviest portion of the well

gas itself including, for example, the C₉ to C₁₄ hydrocarbons is introduced into the top of absorber 13 by means of line 14, and in passing downwardly therethrough in countercurrent contact with the rising gas absorbs heavier constituents. Enriched absorbent is withdrawn from the base of absorber 13 through line 15 and passed to a flash drum 16 maintained at a lower pressure than absorber 13. As the pressure is lowered excessive amounts of undesired light components are vaporized out of the enriched absorbent and are withdrawn from flash drum 16 through line 17 to be disposed of as desired.

Enriched absorbent from which excessively light hydrocarbons have been partially removed is passed via line 18 from flash drum 16 to a stripper 19, wherein absorbed constituents are substantially completely vaporized and driven out of the absorbent, the necessary heat being supplied by a suitable reboiler 20. Stripped absorbent medium is withdrawn from stripper 19 through line 21 and after cooling in cooler 22 is returned for further use in the absorber.

Recovered constituents leave the stripper 19 in vapor form via line 23 and are condensed in condenser 24. The resultant condensate travels via line 25 and joins the primary condensate passing through line 11, preferably for transfer to a stabilizer or other equipment for the removal of remaining "wild" constituents whence a stable product may be withdrawn.

Gas which has been denuded of heavier constituents in absorber 13 passes overhead through line 26 and is fed into the inlet of a compressor 27 which again may be of the reciprocating or turbo type as desired, and recompressed to a sufficiently high pressure for it to be reintroduced through line 28 into an underground reservoir, the same as or adjacent to the one from which it was originally withdrawn. The motive power for compressor 27 is supplied through a shaft 29 or any suitable power transmitting means connected to the expander engine 5, in which the initial expansion of well gas is taking place.

Typical operating conditions will now be given for the exemplary embodiment of the invention just described. As was pointed out with reference to the flow arrangement, these conditions in no sense limit the scope of my invention.

A well gas having the following composition was available under a pressure of 2700 pounds per square inch and at a temperature of 120° F.:

Hydrocarbons	Mol per cent
C ₁	78.7
C ₂	9.7
C ₃	4.1
C ₄	2.4
C ₅ and heavier	5.1
	100.0

This gas was heated in exchanger 2 and heater 4 to approximately 680° F. and in expanding at the rate of 1000 cubic feet per minute (at standard conditions) through work engine 5 to a pressure of 1800 pounds per square inch it generated approximately 38 horse-power.

After transition of exchanger 2 and cooler 8 the expanded gas was at a temperature of about 90° F. and was below its dew point. A liquid comprising about 15.4 mol per cent of the feed was collected in the drum 10, its composition being approximately as follows:

Hydrocarbons	Mol per cent
C ₁	43.4
C ₂	12.1
C ₃	8.8
C ₄	7.5
C ₅ and heavier	28.2
	100.0

10 The composition of the gas leaving drum 10 was approximately as follows:

Hydrocarbons	Mol per cent
C ₁	85.0
C ₂	9.3
C ₃	3.3
C ₄	1.4
C ₅ and heavier	1.0
	100.0

20 In absorber 13 an absorbate of the following approximate composition was picked up by the lean absorbent:

Hydrocarbons	Mol per cent
C ₁	52.0
C ₂	19.6
C ₃	13.9
C ₄	8.0
C ₅ and heavier	7.5
	101.0

35 This absorbate comprised 12 mol per cent of the total feed or 14.2 mol per cent of the feed to the absorber, and as will be seen was a concentrate of the C₄ and heavier hydrocarbons in the well gas.

40 The composition of the absorber dry gas rejected through line 26 was:

Hydrocarbons	Mol per cent
C ₁	90.5
C ₂	7.6
C ₃	1.5
C ₄	.3
C ₅ and heavier	0.1
	100.0

50 This residue gas comprised 86% of the feed to the absorber or 72.6% of the total feed gas. Therefore, for every 1000 cubic feet of feed gas expanded from 2700 to 1800 pounds per square inch through work engine 5 there were 726 cubic

55 feet to be compressed in compressor 27 from 1800 to 3000 pounds, the latter pressure having been found necessary for the return of the residue gas to the ground. At a feed rate of 1000 cubic feet per minute the power required by compressor 27 was 38 horsepower, all of which was supplied through shaft 29 by the expansion of the heated well gas.

60 The power balance obtained in this exemplary operation was due to the selection of 680° F. as the temperature to which the well gas was heated prior to expansion. In the event that a higher percentage of the well gas had remained to be returned to the ground, the load on the compressor would have been greater and more energy would have had to be added to the well gas in the form of heat prior to expansion.

65 The additional heat could then have been provided by heating the well gas to a higher temperature in heater 4. There will be in all cases some temperature adequate to provide sufficient

power during expansion for the recompression step, and as the calculation of the requisite temperature from published hydrocarbon data is within the ability of one skilled in hydrocarbon processes, it need not be enlarged upon herein. Likewise, no detailed description is given of the operating conditions employed in the stripping and subsequent steps, these being relatively independent of the energy-transferring features of the invention and susceptible of considerable variation.

There is, of course, a wide range of pressures within which the absorption step may be practiced, and it will be understood that as the pressure in the absorber is lowered, increasing amounts of power are generated in the expansion of the feed gas and consumed in the recompression of the lean gas. Economic factors will determine what the optimum absorption pressure will be under any given set of circumstances.

It will be seen that by the method of my invention, exemplified in the process described, I am enabled not only to conserve the initial pressure energy of a gas and accomplish a separation of heavy hydrocarbons from light hydrocarbons at a low pressure without having to supply inordinate amounts of energy, but also am able to supply make-up energy in place of that lost due to the inefficiency of the expander and compressor in its cheapest form, i. e., heat. In order to do this I make use of the gas undergoing treatment as a power-generating medium. Even if 100% of the energy liberated by expansion could be recovered and utilized in compression, the energy added as heat would usually be needed in a reservoir repressuring operation, for a pressure greater than that existing in an underground reservoir is necessary to return gas to that reservoir. It is not to be supposed however that all the energy of recompression originates as heat supplied prior to expansion, for a large part of the necessary energy would be liberated in expanding the gas in the absence of the heating step. It is the ability to secure a power balance by adding just the right amount of heat which enhances the energy-conserving feature of my invention.

Numerous alternative schemes may be employed within the scope of my invention, such as the use of interstage heaters on the expander

5 in place of or in addition to heater 4. Such variations will readily occur to those skilled in the art, and as stated earlier, the invention is not limited to any one of the modifications disclosed.

5 I claim:

1. In a process for the recovery of heavier hydrocarbons from a hydrocarbon mixture withdrawn from an underground reservoir, the combination comprising heating said mixture to an elevated temperature prior to separation of heavier hydrocarbons therefrom to materially increase the energy contained therein to a point where no additional energy is required to effect recompression of light constituents as hereinafter specified, thereafter reducing the pressure on the heated mixture, recovering energy from said pressure reduction, separating heavier hydrocarbons from said mixture, and utilizing energy thus recovered as the sole source of power to recompress light constituents remaining after separation of said heavier constituents from the mixture.

15 2. A process in accordance with claim 1 where-in said hydrocarbon mixture is heated to a temperature in excess of 600° F. prior to the expansion thereof.

20 3. A process in accordance with claim 1 where-in a hydrocarbon absorption oil contacts said heated hydrocarbon mixture after expansion thereof to effect separation of heavier hydrocarbons from said mixture.

25 4. In a process for the recovery of heavier hydrocarbons from a hydrocarbon mixture withdrawn from an underground reservoir, the combination comprising heating said mixture to an elevated temperature prior to separation of heavier hydrocarbons therefrom to materially increase the energy contained therein, thereafter reducing the pressure on the heated mixture, recovering energy from said pressure reduction, passing the heated mixture at said reduced pressure into an absorption zone and therein contacting it with an absorption oil to separate heavier constituents contained therein and utilizing energy thus recovered to recompress light constituents remaining after separation of said heavier constituents from the mixture.

PERCIVAL C. KEITH.
